UNITED STATES PATENT OFFICE.

CATHERINE M. LANGHORNE, OF PLAINFIELD, NEW JERSEY.

FOLDING EXTENSION-TABLE.

No. 824,186.

Specification of Letters Patent.

Patented June 26, 1906.

Application filed November 9, 1905. Serial No. 286,475.

To all whom it may concern:

Be it known that I, CATHERINE MUNRO LANGHORNE, a citizen of the United States, and a resident of Plainfield, in the county of 5 Union and State of New Jersey, have invented a certain new and useful Improvement in Folding Extension-Tables, of which the following is a specification.

The object of this invention is to provide 10 an extension-table which in its closed condition will be small and compact and will yet stand upon its own legs and which in its extended position will provide a large surface for work or other purposes.

15 The invention consists of features of construction and arrangements and combinations of devices hereinafter described, and more particularly pointed out in the appended claims.

20 The invention is embodied in the table illustrated in the accompanying drawings, (two sheets,) forming part hereof, in which—

Figure 1 is a plan, partly broken away, of the table extended. Fig. 2 is a side elevation of 25 the same. Fig. 3 is a plan view, partly broken away, of the table closed; and Fig. 4 is an end (side) view of the same.

In the drawings the reference-letter *a* denotes a table-top which is fixed to and is supported by legs *b* *c*, and *d* denotes a set of 30 leaves hinged to each other and to the top *a* by suitable hinges, as *e*, so that they will fold up, as indicated in Figs. 3 and 4, and will extend, as shown in Figs. 1 and 2. Suitable 35 hooks and eyes *f* may be used to retain the leaves *d*, or some of them, in the folded-up position, or other means may be used for this purpose.

The leaves *d* are supported when extended 40 by means of telescoping section *g h i k*, which have legs *l*. The sections *g h i k* may be made in any suitable design and of any material suited to the purpose in view. For small or light tables sheet metal may be used 45 for said sections. Each section consists of a horizontal part which supports directly the leaf *d* thereon and of a vertical part or parts which form the leg or legs *l* of the section. The section *g* is pivotally attached to the top 50 *a*, preferably by means of a shoulder of the leg *c*, between which shoulder and the top *a* the section is placed. The section *h* is arranged in any suitable manner to slide upon the section *g*, the section *i* to slide upon the section *h*, and section *k* to slide upon the sec-

tion *i*. For purposes of illustration the sections *g h i k* are shown as being formed of sheet metal and as being united to slide in the manner described by means of loops *m* on the sections *h i k*, which embrace and 60 slide upon the horizontal parts of the sections *g h i*, respectively.

The described table when closed has a relatively narrow top and may be moved about and be stored at any convenient spot in a 65 room, and the top may be used for a variety of purposes. The table opens out to any extent within the limits of its size, thus being capable when there are three or more leaves *d* of being made into various lengths, as occasion may demand. Thus with four leaves *d* (the number shown in the drawings) the top of the table may be in any one of three sizes—to wit, the size of the top *a*, the size of the top plus the size of two leaves *d*, supported on the 70 sections *g h i k*, (in which case the two end leaves *d* remain folded up,) and the full size. (shown in Figs. 1 and 2.) By having more than four leaves *d* other sizes may be added, and additional sections similar to the sections *g h i k* may be added to provide for the support of such additional leaves.

What I claim as new, and desire to secure by Letters Patent of the United States, is—

1. In an extension-table, the combination 85 with a fixed top and legs fixed thereto, of folding leaves hinged together and to said top, and longitudinally-telescoping leaf-supports adapted to be extended in line and support said leaves, two legs attached to and 90 supporting each of said leaf-supports, the inner leaf-support having pivotal attachment with one of its legs, which leg is rigidly fixed to and adapted to also support the fixed top, whereby the set of leaf-supports may be 95 turned lengthwise of the fixed top and be stowed beneath the same.

2. In an extension-table, the combination with a fixed top and legs fixed thereto, of folding leaves hinged together and to said top, and telescoping leaf-supports provided with 100 legs and pivotally connected to one of the legs fixed to said top, whereby the set of leaf-supports may be turned lengthwise of the fixed top to stow beneath the same.

3. In an extension-table, the combination with a fixed top and legs fixed thereto, of folding leaves hinged together and to said top, and longitudinally-telescoping leaf-supports adapted to be extended in line and sup- 110

port said leaves, two legs attached to and supporting each of said leaf-supports, and the inner leaf-support having pivotal attachment to the said fixed top, whereby the set of leaf-supports may be turned lengthwise of the fixed top and be stowed beneath the same.

Signed at Plainfield, in the county of Union and State of New Jersey, this 28th day of October, A. D. 1905.

CATHERINE M. LANGHORNE.
